COMBINED TIRE TOOL AND DOUBLE WARNING LAMP

Willis E. Green, 7201 Main Ave.,
Orangevale, Calif. 95662

Filed Nov. 3, 1971, Ser. No. 195,531

Term of patent 14 years

Int. Cl. D8—05; D26—99

U.S. Cl. D48—20

FIG. 2

FIG. 1

FIG. 3

FIG. 4

FIG. 5

FIG. 1 is a front elevational view of a combined tire tool and double warning lamp, showing my new design;

FIG. 2 is a top plan view;

FIG. 3 is a bottom plan view;

FIG. 4 is a side elevational view of the left-hand side of FIG. 1; and,

FIG. 5 is a side elevational view of the right-hand side of FIG. 1.

I claim:

The ornamental design for a combined tire tool and double warning lamp, as shown.
